GEORGE C. MCFARLANE, OF SAGINAW, MICHIGAN.

TWO-PHASE PUMPING SYSTEM

No. 895,101.

Specification of Letters Patent.

Patented Aug. 4, 1908.

Application filed January 18, 1908. Serial No. 411,464.

To all whom it may concern:

Be it known that I, GEORGE C. MCFARLANE, a citizen of the United States, residing at Saginaw, in the county of Saginaw and 5 State of Michigan, have invented certain new and useful Improvements in Two - Phase Pumping Systems; and I do hereby declare the following to be a full, clear, and exact description of the invention, such as will enable 10 others skilled in the art to which it appertains to make and use the same.

My invention relates to two phase pumping systems, one object of which is to enable an ordinary pump to be placed a great distance away from and a considerable distance above the water or other liquid to be pumped.

With my system a boiler feed pump might be located several hundred feet above the liquid to be lifted. A mine station pump 20 could be used for raising the water from the bottom of the shaft two- or three-hundred feet below the station. Furthermore, the main station pumps can be employed for lifting liquid from distant sumps below the level 25 of the station.

Another object is to utilize a portion of the liquid lifted to the first station for instance, to draw a full charge into the system.

A still further object is to utilize the force 30 of the injector jet of liquid to compress the air in a suitable chamber to such an extent that the air pressure in such chamber will elevate the full charge to the first station.

Another object attained is the automatic 35 operation of the reversing mechanism, whereby the same pipe or conduit is alternately used for the descending injector jet and the ascending column of water actuated by the pressure in the air chamber.

40 To these and other ends my invention consists in certain novel features and combinations, such as will be more fully described hereinafter and particularly pointed out in the claims.

45 In the accompanying drawings, Figure 1 is a side view showing my invention; Fig. 2 is a top plan view of the reversing gear; Fig. 3 is a cross-section through the reversing gear on the line $x-x$; Fig. 4 is a detail view of the 50 ratchet and pawl mechanism; and Fig. 5 is a perspective detail view of the hooks.

The operation of the system briefly is as follows: The combination of an automatically-actuated reversing gear, with a pump 55 will cause the latter to alternately force water into an elevating pipe and into a dis-

charge pipe respectively. During the first phase, the water forced into the elevating conduit is directed through an injector into an air chamber, the injector and air chamber 60 being placed just above the level of the liquid to be pumped. The passage of the liquid from the injector to the air chamber operates to create a vacuum in a suction chamber to which is connected a suction pipe leading below the surface of the liquid to be pumped. The vacuum draws water through the suction pipe into the chamber where it commingles and is carried with the jet of liquid into the air chamber, compressing the air therein. 70 During the second phase, the pump forces water into the discharge line from a receiving tank and the compressed air in the air chamber operates to force the water therein through a by-pass into the elevating conduit, 75 the latter discharging into the receiving tank from whence it is pumped into the discharge line. Thus it is seen that liquid from the receiving tank is forced down through the injector to draw a further supply into the system and also liquid from the receiving tank 80 is pumped into the discharge line.

(A) indicates a pump cylinder, the piston in which is reciprocated in the usual manner by a steam or other motor (B), piston-rod (1) 85 being shown between the two cylinders. A steam or other power supply pipe (9) leads to the motor (B). A reservoir (2) is located beneath the pump cylinder at any convenient point, the lower end (3) of a suction 90 pipe (4) being submerged beneath the level of liquid in the reservoir, the upper end of the suction pipe communicating with the pumping cylinder. An outlet pipe (5) leads from the pumping cylinder, the outlet pipe communicating respectively with a discharge pipe (6) and with a descending pipe section 95 (7) communicating with the elevating conduit (8).

A reversing gear is operatively associated 100 with the pumping system, one form of such reversing mechanism being constructed as follows: Conveniently suspended above the pump is a bar (10), clamps (11) (11) connecting the bar to the supply pipe (9) and the 105 discharge pipe (6) respectively, for support. Obviously other supports may be utilized in place of the pipes mentioned. Located intermediate the ends of the bar (10) is an inverted U-shaped hanger (12) embracing the 110 bar, the walls of the hanger depending beneath the bar. A shaft (13) is journaled in

the walls of the hanger, a ratchet wheel (14) being keyed to the bar between the walls of the hanger. A spring-pressed pawl (15) pivotally mounted in the hanger prevents back motion of the ratchet. A yoke (16) embraces the ratchet, the ends of the yoke being pivoted on shaft (13), a spring-pressed pawl (17) being pivoted in the yoke and engaging the ratchet to rotate the latter step-by-step. Depending from the yoke is a lever (18) whose lower end lies in juxtaposition to a pin (19) carried, for instance, by the reciprocating piston rod (1). Thus as the piston rod reciprocates, motion will be imparted to the lever to swing it in one direction. The lever might be positively oscillated by the pump or the gravitational force might be depended upon to swing the lever back to the vertical position, but I prefer to employ the following means: Projecting substantially at right angles from the lever is an arm (20), the outer end of which is slotted, as at (21) to loosely receive the lower end of a pin or bolt (22) pivotally secured to the bar (10). A coil spring (23) encircles the pin, one end of the spring bearing against a fixed collar (24), the opposite end of the spring engaging a loose collar (25) slidable on the bolt, the tension of the spring retaining the loose collar in constant engagement with the outer end of the arm (20). An adjustable collar (26) on the lower end of the bolt constitutes a stop against which the outer end of the arm (20) is held by the spring. Movement of the lever (18) toward the right (in Fig. 1) will impart a partial rotation to the ratchet (14) and will simultaneously swing the outer end of the arm (20) upward against the tension of the spring, the bolt moving slightly in the arc of a circle to accommodate the swing of the arm (20). As the arm (20) swings upward it will bear against the loose collar (25) and compress the spring (23). The movement of the pin (19) on the piston rod toward the left (in Fig. 1) would ordinarily leave the lever at its limit of movement, but the force of the spring (23) acting against the arm (20) retains the lower end of the lever against the pin (19) and moves the lever and its pawl (17) back to vertical position. Adjustment of the collar (26) will adjust the throw of the lever and consequently the step-by-step movement imparted to the ratchet.

The shaft (13) projects through the walls of the hanger (12) and disks (27) (27') are secured to each projecting end of such shaft, the disks carrying the laterally extending eccentrically located studs (28^a), the studs being always in alinement with each other. On opposite sides of the hanger (12) are located the hangers (28) (28) and (29) (29) respectively of a general L-shape, the hangers (28) (28) extending laterally away from one side of the bar and then depending in a plane substantially parallel therewith, the hangers

(29) (29) occupying relatively the same positions on the opposite side of the bar. The lower depending ends of the respective hangers or brackets (28) and (29) are slotted, as at (30). Bars (31) and (32) are slidably received in the slots in the respective hangers (28) and (29), the bars extending in opposite directions. To the inner ends of each of the respective bars (31) and (32) are hinge-secured the double hooks (33) (34) and (35) (36), one form of which is shown in Fig. 5. These pairs of hooks are secured to the inner ends of the respective bars (30) and (31) as to have movement in one direction only away from the horizontal. Thus the pair of hooks (33) (34) can swing upwardly above, but not downwardly below the horizontal. On the other hand, the pair of hooks (35) (36) can swing downward below, but not above the horizontal. Leaf-springs (37) carried by the respective bars (31) (32) overlap the respective pairs of hooks to normally retain them in alinement with their supporting bars.

The inner-most hooks (33) and (35) of each pair engage the studs (28^a) of the respective disks (27) (27') the hook (33) taking over its stud (28^a) from above and hook (35) engaging its stud (28^a) from below. The outer-most hooks engage pins (70) as hereinafter set forth. The outer ends of the respective bars (31) and (32) are encircled by springs (38) (38), the inner ends of the springs bearing against the adjacent brackets (28) and (29), respectively, the outer ends of the springs engaging shoulders (39) on the bars. Bar (32) is provided with a slotted extension (40). The steam inlet pipe (9) is equipped with a throttle valve (41) from which a lever (42) extends, the lever having a pin (43) slidingly received in the slot in extension (40).

The discharge pipe (6) and the descending pipe section (7) are each equipped with valves (44) and (45) respectively. The elevating conduit (8) is provided with a branch (46) discharging into the sump or reservoir (2), the branch provided with a valve (47). Valve (44) controls the passage of liquid to the discharge pipe (6); valve (45) controls the passage of liquid from the pump to the descending pipe section (7); and valve (47) controls the admission of liquid from the elevating pipe section to the branch (46) and prevents the admission of liquid from the descending pipe section to the sump (2). These valves may be conveniently located anywhere so long as they accomplish these purposes.

Pivots suspended from the supporting bar (10) by means of links (62) (62) are the connecting rods (63) (64) preferably parallel with each other and lying on opposite sides respectively of the bar (10). The inner ends of the connecting rods are engaged by the links (62), the outer end of each rod being pivotally connected to the adjacent arms of

the respective bell crank levers (65) (65) controlling the valve (44). The opposite arm of one of said bell crank levers (65) is connected by means of a link (66) with the 5 arm of a bell crank lever (67) controlling the valve (45), the remaining arm of said bell crank lever (67) being connected by means of a link (68) with an arm (68^a) controlling valve (47). Each of the connecting links 10 (63) and (64) is provided with an ear (69) carrying a laterally projecting pin (70) adapted to be engaged by the hooks (34) and (36), that is to say, the pin carried by the link (63) is engaged by the hook (34), the pin carried by the link (64) being engaged by the hook (36).

The lower end of the elevating pipe leads to the bottom of the shaft or main reservoir for instance and terminates in an injector 20 nozzle (48) inclosed in a tapering suction chamber (49). A strainer (50) and foot valve (51) are connected to the suction chamber, and the velocity head of the liquid descending through the elevator pipe and 25 issuing through the nozzle (48) will create a suction in the chamber to draw a volume of water through the strainer and past the foot valve into the suction chamber. The mixed liquids (from the elevating pipe and from the 30 reservoir) flow past a check valve (52) located in a pipe (53) leading to an air chamber (54).

Provision may be made for admitting a small quantity of air to the suction chamber 35 (49) by means of a small tube (55) passing into the chamber and terminating in a fine nozzle (56) within the suction chamber, the amount of air being regulated by a valve (57) in the tube. The object of admitting a 40 small quantity of air to the chamber is to replenish the amount of air in the air chamber (54) which may escape with the water from time to time and also to maintain such air fresh and sweet.

45 In order to prevent the liquid in the chamber (49) from kicking back through the air inlet nozzle (56), I may place a check valve (58) in the tube (55). And in order to relieve the air chamber (54) of surplus air 50 drawn in through the nozzle (56) I equip such chamber with an air relief valve (59). Normally the air chamber (54) will be filled with compressed air above the level of the air relief valve (59). A by-pass (60) leads 55 from pipe (53) to the elevating conduit (8), the by-pass having a check valve (61) therein to prevent descending liquid in the elevating conduit from passing through the by-pass.

The operation of my invention is as follows: Assuming the parts to be in the position shown in Fig. 1, the piston rod (1) moving in the direction of the arrow. Also assume that the pump (A) has drawn in a charge of liquid from the receiving tank or 60 sump (2) which will be expelled as the piston

travels toward the right (in the drawings). The expulsion stroke of the piston, therefore, will bring the pin (19) into engagement with the lever (18), causing the pawl (17) engaging the ratchet (14) to partially rotate 70 the latter and with it the disks (27) (27') carrying the pins (28^a) (28^a) in a counter-clockwise direction. From an inspection of the parts it will be seen that the further rotation of disk (27) in the direction of the arrow 75 will operate to release the pin (28^a) carried by the disk from the hook (33). This allows the full tension of the compressed spring (38) to be brought against the bar (31) drawing 80 said bar and its hooks (33) (34) with it toward the right, in the drawings. The hook (34) engaging the pin (70) on link (63) carries the link also toward the right, which through the mechanism described operates to close valves (44) and (47) and open valve 85 (45). This movement need not necessarily be timed with any particular expulsion or suction stroke as the piston makes several strokes when the valves are in either of their two positions, nor need the movement of the 90 valves be timed with regard to the commencement of such expulsion stroke as they can be operated during such a stroke to reverse the pump and shunt the liquid from the discharge pipe (6) to the elevating pipe (7) or 95 from the pump to the discharge pipe. The compressed spring (38) having drawn the connecting link (63) toward the right with the result noted, the pump continues to 100 draw water from the tank (2) and delivers it through elevating pipe (8) to the injector nozzle (48). The liquid issuing from the injector nozzle under great pressure operates to draw additional liquid through the strainer (50) into the suction chamber (49) where it mingles with the injected liquid and is carried past the check valve (52) into the air chamber (54) compressing the air therein. The force of the water descending in pipe (8) aids the spring of check 105 valve (61) to retain the valve closed against the constantly-increasing pressure exerted by the water in the air chamber (54) and bypass (60).

When the connecting link (63) moved toward the right under the pressure of the spring (38), it ceased its movement with the hook (33) overlapping the right-hand side of the disk (27). While the pump continued to force water down the pipe (8) the ratchet 110 was operated to bring the pin (28^a) on disk (27) around to the hook (33) and as the pin (28^a) passes above the horizontal diameter of the disk it is engaged by the hook. Further rotary movement of the disk will bend 115 the hook (33) against the tension of the spring (37) and draw the bar (31) toward the left to the position shown in Fig. 1 to compress spring (38). As the hooks (33) and (34) are connected through the bar (31) the 120

125

130

hook (34) is moved to the left also. The link (63) is returned to the position shown in Fig. 1, by the operation of link (64), as hereinafter explained, the hook (34) taking over 5 the pin (70) at the limit of its movement toward the left. The closing of valves (44) and (47) and the opening of valve (45) when the link (63) is moved toward the right caused the liquid from the pump to travel 10 through pipe (5) to pipes (7) and (8) and down such pipes to the injector. When valves (47) and (44) are opened and valve (45) is closed, the descending column of liquid in pipe (8) is shut off, the liquid then 15 being pumped through discharge pipe (6). As soon as the pressure of the liquid column in pipe (8) is relieved the compressed air in chamber (54) forces the commingled injected liquid and new charge through by-pass (60) 20 and up the elevating pipe (7) to the branch (46) leading to tank (2), replenishing the tank with liquid as it is emptied by the suction pipe (4) and forced out through pipe (6). The disk (27') rotates with disk (27) and as 25 the pin on disk (27) releases itself from the hook (33), the pin (28^a) on disk (27') is just engaging the hook (35) to draw it toward the right together with the bar (32) to compress spring (38). When the disk (27') has rotated 30 so that its pin (28^a) passes above the horizontal diameter of the disk, the hook (35) is released from the pin, allowing the bar (32) to be moved toward the left under the tension of the spring (38). Link (64) similar to 35 link (63) is connected to the bellcrank (65) controlling valve (44), the hook (36) of the bar (32) taking over a pin (70) carried by such link (64). Hence just as the pin (28^a) of disk (27) is picking up the hook (33) of bar 40 (31), pin (28^a) on disk (27') releases hook (35) of bar (32), whereby to reverse the pump by closing valve (45) and opening valves (44) and (47). The movement of link (64) to the left throws link (63) back to its 45 position (shown in Fig. 1), since both links are connected through the valve (44) and bell cranks (65). Obviously movement of the link (63) to the right will carry with it the link (64) to a position where the pin (70) on link (64) can be engaged by the hook (36). In this way the pump is reversed.

It will be remembered that if desired, the sliding bar (32) may have a slotted extension (40) which slot receives a pin (43) carried by a lever (42) controlling the steam supply to the pump. When the pump is delivering liquid through the discharge pipe (6), it may be that less pressure will be needed than when the pump is delivering water to 60 the elevating pipe (8). Therefore, as the valves (44) and (47) are opened the throttle valve (41) controlling the steam supply is partially closed to slow down the pump.

While the disks (27) (27') make one-half a 65 revolution, the pump is forcing water down

pipe (8) and during the other half of the revolution the pump forces water out through pipe (6). The number of strokes of the piston necessary to drive the disks through a half revolution is determined by 70 the throw of the lever (18). The quantity of liquid forced through the injector is intended to draw in an approximately similar quantity through the foot valve. During the second phase the full quantity of liquid in the 75 air-chamber (54) is forced up through the elevator pipe (8). By adjusting the slotted extension (40), the valve (41) may be operated on either phase of movement of the pump, depending upon which phase requires 80 the expenditure of the most power.

The general arrangement of parts may be varied and certain of the elements omitted without departing from the spirit and scope of my invention.

Having thus fully disclosed my invention, what I claim as new is—

1. A pumping system comprising a pump, a discharge conduit leading therefrom, a receiving tank, a suction pipe from the pump 90 to the tank, an air chamber, a suction chamber communicating therewith, a foot valve communicating with the suction chamber, an elevating pipe connecting the discharge conduit and suction chamber, the elevating pipe 95 terminating in an injector within the suction chamber, a by-pass around the suction chamber connecting the air chamber to the elevating pipe, a check valve in the by-pass, a branch leading from the elevating pipe to the 100 tank, valves in the branch and in the elevating pipe and reversing gear actuated by the pump for reversing the valves.

2. A pumping system comprising a pump, an air chamber, means connecting the pump 105 and air chamber, a suction device interposed in said connecting means, a by-pass around said suction device, a receiving tank from which the pump draws its supply, a branch leading from the connecting means to the 110 tank, valves in the connecting means and in the branch and reversing mechanism controlled by the pump for operating the valves.

3. A pumping system comprising a pump located at a distance from the source of supply, an air chamber located adjacent the source of supply, means for conducting a jet of liquid under pressure from the pump to the air chamber, a suction device interposed in the conducting means to permit the jet to 120 draw a volume of liquid from the source into the air chamber, a tank into which the air chamber discharges its contents, valves in the conducting means and in the discharge from the air chamber to the tank, and reversing gear controlled by the pump for actuating the valves.

4. A two-phase pumping system comprising a pump, an air chamber, a conduit connecting the pump and air chamber, a suction 13

means interposed in the conduit, the suction means connected with a source of supply, a discharge pipe in communication with the pump, a tank into which the air chamber discharges, valves controlling the direction of flow of the liquid delivered from the pump, and reversing mechanism controlled by the pump for actuating the valves.

5. A two-phase pumping system comprising a pump, a supply tank for the pump, a pipe leading from the tank to the pump, a main supply located some distance beneath the pump, a suction chamber communicating with the main supply, an air chamber in communication with the suction chamber, a connection leading from the pump to the suction chamber, a by-pass around the suction chamber from the air chamber to the pump connection, a check valve in the by-pass, a 10 branch leading from the connection to the supply tank, a valve in the branch, a valve in the pump connection above the branch, an automatic reversing gear actuated by the pump, a linkage connecting the reversing 15 gear and the valves in the pump connection and in the branch, and a discharge leading from the pump connection.

6. A pumping system comprising a pump, a main supply located some distance away from and beneath the pump, a supply tank communicating with the pump, a suction chamber communicating with the main supply, an injector extending into the suction chamber, an air chamber communicating 20 with the suction chamber opposite the injector, a pump connection from the pump to the injector and adapted to alternately convey descending and ascending columns of liquid, a discharge pipe communicating with the connection, a branch leading from the connection to the supply tank, valves in the branch and in the connection above the branch respectively, a reversing gear actuated by the pump, a linkage connecting the 25 reversing gear and valves to alternately open one and close the other automatically and a by-pass leading from the air chamber around the suction chamber to the pump connection.

7. In a pumping system, the combination 30 with a pump, of a suction chamber in communication with a source of liquid supply, an air chamber communicating with the suction chamber, a connection from the pump to the suction chamber, means for admitting air to the suction chamber, means for permitting the escape of air from the air chamber, and a by-pass from the air chamber to the pump connection.

8. In a pumping system, the combination 35 with a pump, of a suction chamber in communication with a source of liquid supply, an air chamber communicating with the suction chamber, a connection from the pump to the suction chamber, means for admitting air to the suction chamber, a check valve in said

air admission means, means for permitting the escape of air from the air chamber, and a by-pass from the air chamber to the pump connection.

9. In a pumping system, the combination 40 with a pump, of a suction chamber in communication with a source of liquid supply, an air chamber communicating with the suction chamber, a connection from the pump to the suction chamber, means for admitting air to the suction chamber, means for permitting the escape of air from the air chamber, and a by-pass from the air chamber to the pump connection, and a check valve in the by-pass.

10. A pumping system comprising a pump, 45 a main supply located at a distance, a supply tank communicating with the pump, an air chamber adjacent the main supply, a conductor leading from the pump to the air chamber and communicating with the main supply for storing a charge of liquid from the pump and from the main supply in the air chamber, a separate connection between the air chamber and the conductor, a branch leading from the conductor to the tank, a 50 discharge pipe leading from the conductor, valves in the conductor and in the branch for controlling the passage of liquid up or down in the conductor, a reversing mechanism actuated by the pump, and a linkage connecting the valves and reversing mechanism.

11. A two-phase pumping system comprising a pump, a main supply located at a distance, an air chamber, a conductor from the pump to the air chamber, the conductor 55 in communication with the main supply, a by-pass between the conductor and the air chamber, a supply tank in communication with the pump, a discharge from the conductor to the supply tank, valves controlling the direction of flow of liquid in the conductor and reversing mechanism connected with the valves.

12. A reversing mechanism for pumping systems comprising a valve mechanism, suitably suspended connecting links secured thereto, separate power actuated means adapted to engage the respective links, a rotatable member, means on the rotatable member adapted to engage the power-actuated means to alternately store power in one or the other, and means for actuating the rotatable member.

13. The combination with a valve mechanism, of a pair of suitably-supported connecting links secured thereto, oppositely mounted slidable bars, springs adapted to actuate the respective bars in opposite directions, means carried by the bars adapted to releasably engage the respective connecting links, and a rotatable member adapted to releasably engage the respective sliding bars alternately to store energy in their respective springs.

14. A pumping system comprising a pump,

- a liquid supply for the pump, a water elevator, a conductor leading from the pump to the elevator, a discharge leading from the conductor, valves controlling the direction of flow of the liquid from the pump, a reversing mechanism for operating the valves, means for introducing liquid from a main supply into the conductor, and a pipe for conveying liquid from the elevator.
- 10 15. A two phase pumping system comprising a conductor, separate pumping means for forcing liquid alternately in opposite directions in the conductor, an intake communicating with one of said pumping means, means for introducing liquid from a main liquid supply into the conductor to supply the remaining pumping means, a discharge pipe from the conductor, a delivery pipe connecting one of said pumping means and the conductor, valves for controlling the direction of movement of liquid in the conductor, and reversing mechanism actuated by one of said pumping means for controlling the valves.
- 15 20 25 30 35 40 45 50 55 60 65 70 75 80 85 90 95 100 105 110 115 120 125 130
16. A two-phase pumping system comprising a conductor, separate pumping means located at opposite ends of the conductor for forcing liquid alternately in opposite directions therethrough, means for introducing liquid from a main supply into the conductor adjacent one of the pumping means, an intake communicating with the other of the pumping means, valves controlling the direction of flow of the liquid in the conductor, a discharge pipe, and a reversing mechanism for simultaneously operating the valves.
17. A reversing mechanism comprising a valve apparatus, a pair of reciprocating links connected therewith so that the movement of one link will actuate the other through the valve apparatus, oppositely disposed spring actuated members adapted to engage respective links, a rotatable member adapted to releasably engage the spring-actuated members to alternately place the springs under tension, and means for operating the rotatable member.
18. A reversing mechanism comprising a suitable frame, a ratchet journaled in the frame, means for actuating the ratchet, disks keyed with the ratchet, a pin projecting from each disk, oppositely extending bars yieldingly mounted in the frame, each bar carrying a spring, a pair of hooks pivotally secured to each bar, the hooks on the bars capable of a movement in one direction only from the longitudinal axis of the bar, the arcs of movement of the hooks on the respective bars being opposite one another, means for yieldingly retaining the hooks in alignment with the bars, one of each pair of hooks adapted to be releasably engaged by the pin of its adjacent disk to place the springs under tension, a valve, connecting links at-
- tached to the valve, and pins on the links engaged by the remaining member of the respective pairs of hooks as the pin on the adjacent disk disengages itself from the other member of the respective pairs of hooks, the sliding bars being alternately reciprocated to actuate the valve.
19. A pumping system comprising a pump, a liquid supply therefor, a conductor in communication with the pump, a discharge leading from the conductor, valves controlling the direction of flow of liquid in the conductor, a reversing mechanism controlling the valves and a water elevating means in communication with a main supply, means communicating with the conductor for introducing liquid from the main supply into the water elevating means, the water elevating means being actuated by liquid under pressure from the conductor.
20. A two-phase pumping system comprising a pump, a liquid supply therefor, a conductor communicating with the pump, a discharge pipe for liquid from the pump, valves controlling the flow of liquid to the discharge or to the conductor, a reversing mechanism actuated by the pump for controlling the valves, a water elevator, the conductor communicating with the water elevator and with a liquid supply therefor, means for introducing liquid from a main supply into the conductor, a connection leading directly from the water elevator to the conductor and a branch discharge from the conductor for liquid from the water elevator.
21. A two-phase pumping system comprising a conductor, separate pumping means located at and in communication with the opposite ends of the conductor for forcing liquid alternately in opposite directions therethrough, the conductor being in communication with a main supply adjacent one of the pumping means, a reservoir, means connecting one of the pumping means with the reservoir, a discharge pipe leading from a point intermediate the ends of the conductor to the reservoir, valves controlling the direction of flow of the liquid in the conductor, means in the conductor connected with a main liquid supply for introducing liquid therefrom into the conductor, a reversing mechanism for simultaneously operating the valves, and a discharge pipe for the liquid introduced into the system from the main supply.
22. A pumping system comprising a pump, a liquid supply therefor, a conductor into which the pump ejects liquid, one end of the conductor constituting a discharge, a water elevating member to which the opposite end of the conductor leads, an injector in the conductor, the injector communicating with a main liquid supply, a pipe leading from a point intermediate the ends of the conductor to the liquid supply for the

pump, a series of valves controlling the direction of flow of the liquid in the conductor, and a reversing mechanism controlling the valves.

5 23. In a reversing mechanism for pumps, the combination with a valve, of a revolute member, sliding bars, means for moving the bars in opposite directions, a plurality of hooks carried by each of the respective 10 bars, one hook on each bar adapted to be releasably engaged by the revolute member to store power in the bar-actuating means, and connecting links secured to the valve, the respective links adapted to be engaged 15 by the remaining hook on the respective adjacent bars.

24. A pumping system comprising a pump, a conductor communicating therewith, valves in the conductor controlling 20 the direction of flow of liquid, a motor for actuating the pump, a steam supply for the motor, a valve in the steam supply, and a reversing gear for simultaneously actuating the valve in the conductor and the valve 25 in the steam supply.

25. In a pumping system, the combination of a pump, a conductor communicating therewith, valves in the conductor controlling the direction of flow of liquid, a motor 30 for actuating the pump, a steam supply for the motor, a valve in the steam supply and a reversing gear comprising a plurality of spring actuated bars, links adapted to be engaged by the bars, suitably actuated 35 means engaging the bars for placing their springs under tension and then releasing the bars, the links connected with the valves in the conductor, an extension carried by one of the bars, and a lever connected to 40 the valve in the steam supply and slidably engaged by the extension.

26. In a reversing mechanism for pumps, the combination with a valve, of spring-actuated bars movable in opposite directions, links connected to the valve, means 45 engaging the bars for placing their springs under tension and then releasing the bars, the bars adapted to engage and draw the links with them to actuate the valve.

50 27. A pumping system comprising a pump, an injector mechanism communicating with a main liquid supply, a conductor connecting the pump and injector, the pump adapted to force liquid through the 55 conductor to the injector, an air chamber

into which the injector discharges, a check valve interposed between the injector and the air chamber, a pipe for conveying liquid from the air chamber, and a valve in the pipe.

60 28. A pumping system comprising a pump, an injector, a conductor connecting the pump and injector, a discharge from the conductor intermediate the pipe and injector, an air chamber in which the liquid 65 from the injector is received, the injector communicating with a liquid supply to draw liquid therefrom and force it into the air chamber, a check valve interposed between the injector and air chamber, a by-pass leading from the air chamber to the conductor around the injector, a check valve in the by-pass, an extension of the conductor constituting a discharge from the pump, valves located in the conductor 70 on opposite sides of its connection with the pump, a valve controlling the discharge from the conductor intermediate the pump and the injector, and an automatic reversing mechanism for controlling the valves 75 to change the direction of flow of liquid in the conductor.

29. A pumping system comprising a pump, an injector, mechanism communicating with a main liquid supply, a conductor 80 connecting the pump and injector, the pump adapted to force liquid through the conductor to the injector, an air chamber into which the injector discharges, means 85 for supplying air to the air chamber, a check valve interposed between the injector and the air chamber, a pipe for conveying liquid 90 from the air chamber, and a valve in the pipe.

30. A pumping system comprising a pump, a liquid supply therefor, a conductor 95 into which the pump ejects liquid, one end of the conductor constituting a discharge, a water elevating member to which the opposite end of the conductor leads, an injector in the conductor, the injector communicating with a main liquid supply, and a series of valves controlling the direction of flow of the liquid in the conductor.

In testimony whereof, I affix my signature in presence of two witnesses.

GEORGE C. MFARLANE.
